UNITED STATES PATENT OFFICE.

HENRY TEXTOR, OF BROOKLYN, NEW YORK.

SEWER-TRAP.

SPECIFICATION forming part of Letters Patent No. 373,952, dated November 29, 1887.

Application filed May 2, 1887. Serial No. 236,818. (No model.)

To all whom it may concern:

Be it known that I, HENRY TEXTOR, of Brooklyn, in the county of Kings and State of New York, have invented certain new and 5 useful Improvements in Sewer-Traps, of which the following is a specification.

This invention relates to new and useful improvements in that class of sewer-traps that are attached to the ends of pipes for draining the 10 water from cellars to the sewer and preventing the backwater from the sewer from passing into the cellar.

The object of my invention is to provide a new and improved trap of this kind which is 15 simple in construction, effective in use, and which can be fastened easily and with an absolutely tight joint to the end of the pipe leading to the sewer.

The invention consists in the combination, 20 with a cylindrical vessel containing a cone, a float, and a top plate having a seat for said cone, of a detachable neck on the bottom of said vessel, which neck is to be fastened to the end of the pipe that leads to the sewer, a de- 25 tachable bell covering the vessel, and a basin surrounding said cylinder.

The invention also consists in the construction and combination of parts and details, as will be fully described hereinafter, and then 30 pointed out in the claims.

In the accompanying drawings, Figure 1 is a cross-sectional view of my improved sewer-trap. Fig. 2 is a sectional plan view of the same on line $x\ x$, Fig. 1; and Fig. 3 is a detail 35 side view of part of the locking device, parts being broken out and others in section.

Similar letters of reference indicate corresponding parts.

The cup-shaped vessel or basin A is provided with a central bottom opening, A', from 40 the edge of which a series of apertured lugs or wings, A², project into said opening. The cylinder B is of less diameter than the basin A, is provided with an exterior top flange, B', and an interior bottom flange, B², the latter being provided with a series of apertures, through which the screw-bolts C are passed, which are also passed through apertures in the bottom of the basin A, the heads of said 45 bolts being countersunk in the under side of the bottom of the basin A. The cylinder B is

thus securely fastened in the said basin A. The exterior top flange, B', is provided with two opposite notches, D, and from said notches the height or thickness of said flange gradually increases, as shown at D' in Fig. 3. The top plate, E, of the cylinder B is inclined from the rim down to a central opening, E', and at the rim it is provided with the upwardly-projecting flange F. The cover G, which has numerous apertures, G', rests upon the flange F, and is provided with two opposite downwardly-projecting hooks, H, which can be passed through the notches D in the top flange, B', and can engage the bottom of said flange. 55

The cover G is provided on its upper surface with the upwardly-projecting lugs I, which are to be used in turning the top plate, and upon said lugs a bell, J, rests, the diameter of which is greater than that of the cylinder B, 60 to allow the water to flow out. To prevent the bell from shifting laterally lugs K are provided on the inside of the same, which rest against the rim of the cover G. 65

In the vessel B, I provide the float L, having a downwardly-projecting stem, L', which is passed through an aperture in a cross-frame, M', attached to a sheet-metal cone of copper, M, in the cylinder B, whereby the stem of the float is guided. The float finds its seating on 70 the edge of the aperture E' in the top plate, E. The neck N fits in the socket O' at the end of the pipe that leads to the sewer. It is provided at its top edge with as many inwardly-projecting apertured lugs P as there are lugs 75 A² at the bottom opening of the basin A. The neck N is placed into the socket O' and calked, so as to form an absolutely tight joint. Then the basin A is placed upon the top of the neck N and screw-bolts R passed through the apertures of the corresponding lugs A² and P, and nuts R' are screwed on the upper ends of said lug-bolts, whereby the basin A is held firmly and securely on the neck N. The top plate, E, is placed upon the washer-rings S S of the 80 flange B' and the cover G placed above the top plate, the hooks H passing through the notches D in the flange B', and then the said cover is turned axially, whereby it is pressed upon the top edge of the flange F of the top plate, E, 85 and said top plate is pressed upon the washer-ring S, which in turn is pressed upon the flange 90

95 flange B' and the cover G placed above the top plate, the hooks H passing through the notches D in the flange B', and then the said cover is turned axially, whereby it is pressed upon the top edge of the flange F of the top plate, E, 100 and said top plate is pressed upon the washer-ring S, which in turn is pressed upon the flange

m of the cone M and the top flange, B', and thus a tight joint is formed. The bell J is then placed upon the cover G and the basin covered by a strainer of the usual construction. 5 The water in the cellar, &c., flows in the basin A through the strainer above the bell J, and down over the same, and rises in the vessel A, finally flowing through large apertures in the cover G on the top plate, E, and through the opening E' in the same to the conducting-pipe. When any backwater passes from the sewer into the trap, it raises the float and presses the same against its seat, thus preventing said backwater from flowing into the cellar. As 15 soon as the backwater flows off, the float drops, and the water from the cellar can pass off through the trap.

One of the special advantages of my trap is, that the neck can be calked and secured in 20 the socket O and the vessel A then fastened on said neck.

By making the cylinder B in such a manner 25 that it can be bolted to the vessel the casting of the parts and working is materially simplified and the cost of making the trap reduced.

Having thus described my invention, I claim as new and desire to secure by Letters Patent—

1. In a sewer-trap, the combination, with a cup-shaped basin, A, of the cylinder B in the same, the top plate, E, the float L, the cover G, provided with upwardly-projecting lugs, and the bell J, resting upon said lugs, substantially as herein shown and described. 30

2. In a sewer-trap, the combination, with a cup-shaped basin, A, of the cylinder B, provided with an exterior top flange, B', and the interior bottom flange, B, the top plate, E, the float L, and the cover G, having lugs which can be engaged with top flange, substantially as herein shown and described. 35

In testimony that I claim the foregoing as my invention I have signed my name in presence of two subscribing witnesses.

HY. TEXTOR.
